UNITED STATES PATENT OFFICE.

WILEY W. PRINCE, OF ELLISVILLE, MISSISSIPPI.

GATE-LATCH.

1,074,013.

Specification of Letters Patent.

Patented Sept. 23, 1913.

Application filed June 4, 1912. Serial No. 701,623.

To all whom it may concern:

Be it known that I, WILEY W. PRINCE, a citizen of the United States, residing at Ellisville, in the county of Jones and State 5 of Mississippi, have invented new and useful Improvements in Gate-Latches, of which the following is a specification.

The general object of the invention is to increase the efficiency of gate latches, and 10 particularly those of the automatic locking and gravity type by providing a construction which may be readily applied to a gate post and effectively held against disengagement therefrom.

15 Other objects will appear and be better understood from the following description taken in connection with the accompanying drawings in which:

Figure 1 is a perspective of the device applied to a gate structure. Fig. 2 is a horizontal section taken through the gate post showing how the device is secured therein. Fig. 3 is a detail longitudinal section of the device and Fig. 4 is a detail plan of a blank 25 from which the ring holder may be formed.

a indicates the holder for the latch which is herein shown to constitute a ring 5. The holder a is hollow and by preference rectangular in cross section and formed with 30 elong slots 6 arranged in the opposite sides 7 thereof.

8 indicates a pin passing through the holder and suitably secured therein, such as by upsetting the ends thereof. The said pin 35 is adapted to support the latch 5 which freely moves through the holder and slots thereof, and the pin is arranged so that when the ring is moved outwardly the upper segment thereof will abut the outer end 40 of the lower slot whereby to prevent upward movement of the ring, but when the ring is moved rearwardly it will turn on the pin as a pivot and pass upwardly, the slots of course, being sufficient in length to permit 45 this action of the ring.

The outer end of the holder receives a head 10 which is of hardened metal and serves as a driving head to receive the blows of the hammer while the holder is being 50 driven into the post b. The inner end of the holder has diverging prongs which are sharpened and adapted to readily enter the wood of the post b when the head 10 is struck by the hammer.

55 12 indicates prongs extending laterally from opposite faces of the holder which ex-

tend so as to interlock with the side of the wall formed by driving the inner end of the holder into the post whereby to prevent the holder from being retracted when the gate 60 c is pulled outwardly and the keeper d thereof abuts the latch and the ring 5.

If desired, the holder may be formed of a blank of sheet metal which is shown in Fig. 4. In this instance the blank f is oblong and formed centrally with a longitudinal slot 13, the sides of the blank having recesses 14 corresponding in length to the slot 13.

15 indicates a recess extending from one 70 end of the blank, and 17 indicates sharpened edges on one end of the blank and to either side of the recess 15. The blank thus described may be stamped from a sheet of metal and constructed as shown, with perhaps 75 two operations, after which the blank is bent upon itself on a line passing through the middle of the slot 13, after which, the portions to each side of the recesses 14 are bent inwardly so that the edges of the bent 80 portions of one side of the blank will but the edges of the bent portions on the other side of the blank. In this connection it will be observed, that the sides of the recesses 14 will form opposite sides of the slot which 85 parallels the slot 13. The blank as shown in Fig. 4, is formed with openings 18 to receive a pin similar to the pin 8, which, like the latter, serves as a support for the latch and additionally serves to connect the sides 90 of the blank.

It is to be particularly noted that the distance between the pin 8 and the edge 7, is greater than the diameter of the ring, while the distance from said pin 8 to the corresponding edge of the head 10 is materially less than the diameter of the ring 8. This is an important feature of the present construction as by it I am enabled to permit the latch bar d to coöperate with the ring 100 for latching function above the diametrical line of said ring in parallelism to the bar a. It is therefore impossible for the latch bar, in the tendency of the gate to open, to raise the ring, as it coöperates with the edge above 105 the diametrical line noted and therefore can only have a swinging effect. In order to secure this result it is absolutely necessary that the ring be free to swing wholly upward when the latch engages the forward 110 edge of the ring in moving into latching position, for as previously stated in such move-

ment the latch bar *d* engages the ring above the diametric line parallel to the bar *a* and hence cannot exert a lifting action but only a swinging action. This invention is therefore to be distinguished from those constructions in which the ring is capable of and adapted for a lifting rather than a swinging movement, as in such lifting constructions the latch bar will necessarily open, or 10 actuate the ring to open the connection, as readily as it closes.

Although I have shown and described one embodiment of the invention, it is to be understood that I am not to be limited to any 15 specific structure, since it will be observed that various changes will be made within the scope of the appended claim without departing from the spirit or sacrificing any of the advantages of the invention.

Having thus described the invention what 20 I claim is:—

A latch member constructed of a single blank and including spaced arms having their marginal edges free of connection for the greater portions of their lengths, one 25 terminal of the arm having its upper and lower marginal edges connected to form a driving head and the opposing terminal having an entrant member, the arms in their unconnected edge portions being united by 30 transverse pivot pin and a ring loosely supported on said pin.

In testimony whereof I affix my signature in presence of two witnesses.

WILEY W. PRINCE.
